INSTRUMENT CASE

E. Burton Benjamin, Chicago, Ill., assignor to H. & A. Selmer, Inc., Elkhart, Ind., a corporation of Indiana

Filed Aug. 24, 1960, Ser. No. 61,873

Term of patent 14 years

(Cl. D87—5)

FIGURE 1 is a front elevation of an instrument case showing the essential features of my new design in full lines;

FIGURE 2 is a perspective view of the ornamental instrument case;

FIGURE 3 is an end elevation of my ornamental instrument case; and

FIGURE 4 is an enlarged fragmentary cross sectional view taken substantially on the line IV—IV looking in the direction indicated by the arrows, as seen in FIGURE 1.

The rear view of the instrument case is the same as the front view and the bottom of the case is like the top of the case except that latch and hinge fittings are not employed.

I claim:

The ornamental design for an instrument case or similar article, as shown and described.
